DESIGN FOR A DRY SHAVER CASING

Georges Wilmet, New York, N. Y., assignor to American Safety Razor Corporation, Brooklyn,
N. Y., a corporation of Virginia

Application October 12, 1937, Serial No. 72,133

Term of patent 14 years

To all whom it may concern:

Be it known that I, Georges Wilmet, a subject of the King of Belgium and a resident of the city, county, and State of New York, have invented a new, original, and ornamental Design for a Dry Shaver Casing, of which the following is a specification, reference being had to the accompanying drawing, forming part thereof.

I claim:

The ornamental design for a dry shaver casing as shown.

GEORGES WILMET.
